UNITED STATES PATENT OFFICE.

DONALD W. ROSS, OF CHICAGO, ILLINOIS.

ATTACHMENT FOR GAS-STOVES.

SPECIFICATION forming part of Letters Patent No. 729,670, dated June 2, 1903.

Application filed May 17, 1902. Serial No. 107,789. (No models.)

To all whom it may concern:

Be it known that I, DONALD W. ROSS, a citizen of the United States, residing at Chicago, in the county of Cook and State of Illinois, 5 have invented a new and useful Attachment for Gas-Stoves, of which the following is a specification.

This invention relates generally to gas-stoves, and is in the nature of a regulator for governing the amount of gas passing to the burner, the object being to provide a cheap and simple appliance capable of attachment to the ordinary gas-stoves now in use, and by means of which the full flow of gas is permitted when an article to be heated is placed upon the stove and a reduced quantity of gas fed to the burner when the said article is removed, thereby economizing in the use of the gas and also avoiding the necessity of cutting off the gas and relighting the burner each and every time an article to be heated is replaced or removed.

My invention is particularly adapted for the use of tailors, bookbinders, and the like; 25 and it consists in the novel features of construction, combination, or arrangement, all of which will be fully described hereinafter and pointed out in the claims.

In the drawings forming part of this specification, Figure 1 is an inverted plan view of a gas-stove provided with my improvement. Fig. 2 is a sectional view of the same, the parts being shown in elevation. Fig. 3 is a sectional view illustrating the movable rest 35 and tripping-lever. Fig. 4 is a detail perspective view of the movable rest. Fig. 5 is a detail perspective view of the sleeve in which the shaft of the rest moves. Fig. 6 is a detail perspective view of the lever. Fig. 40 7 is a detail view of the bracket. Fig. 8 is a top plan view of the cut-off valve, showing the upright rod and spring connected thereto.

Referring to the drawings, A indicates the base or platform of an ordinary gas-stove having the double burner A' A'', to which the pipes A³ and A⁴, respectively, lead, said pipes being connected to the union-pipe A⁵, having the usual construction of needle-valves A⁶. A gas-supply pipe B leads to the union-pipe 45 A⁵ and has a cut-off valve C arranged therein, said valve having the arms C' and C'' extending therefrom, the arms C' having a rod

D connected thereto, while the arms C² have a spiral spring E. The opposite end of the spring E is connected to the base or frame of the stove, and the normal tendency of the 55 said spring is to throw the valve in such position that the flow of gas therethrough will be nearly, but not entirely, cut off. The opposite end of the rod D is connected to a depending portion F' of a lever F, which is pivoted to the end of a bracket G, which is securely fastened to the bracket H, carrying the burner A'. This lever F has a weight F² at its outer end and at its inner end is flattened, 60 as shown at F³, to engage the lower end of a shaft I, carrying a support K at its upper end, said support being intended to receive the article to be heated. The shaft I works loosely in a sleeve L, fitted in the central 65 opening of the burner A², said sleeve having a slot L' produced therein adjacent to its upper end and in which works the guide-pin I', limiting the upward and downward movement of the shaft I and support K. A washer 70 L² surrounds the lower end of sleeve L. In operation when an article to be heated is placed upon the support said support is depressed by the weight of the article, forcing the shaft I downwardly, and the lower end of 75 the shaft pressing upon the plate F³ at the end of the lever F depresses said lever, forcing the depending portion F' rearwardly or downwardly and pulling upon the rod D, which opens the valve, permitting the full 80 force of gas to flow therethrough, thus producing a flame of maximum intensity. When the article is removed, the weight F² of the lever F immediately raises the support to the 85 position shown in dotted lines in Fig. 3, and the spring E, together with the action of the rod D, will operate the valve C, so as to cut off the greater portion of the supply of gas, 90 thus permitting the burner to continue lighted, but with a greatly-reduced flame.

It will thus be seen that by means of my improved attachment the stove can be kept lighted always, and by automatically regulating the supply of gas a great deal of time and labor is saved and likewise a great deal 95 of gas.

Having thus fully described my invention, what I claim as new, and desire to secure by Letters Patent, is—

1. The combination with a gas-stove, of a movable support having a depending shaft, a sleeve in which the shaft moves, said sleeve being slotted, a stop or guide pin passing 5 through the depending shaft and working in the slot, a lever pivotally supported beneath the stove, weighted at one end, the opposite end being shaped for engagement with the lower end of the depending shaft, said lever 10 having depending portion, an operating-rod connected to said depending portion, a regulating-valve arranged in the supply-pipe of the stove and having oppositely-disposed arms, the operating-rod being connected to 15 one arm, and a spiral spring connected to the opposite arm, substantially as specified.
2. The combination with a gas-stove, a supply-pipe, a cut-off valve arranged therein, arms attached thereto, a spring attached to one arm, a rod attached to the other arm, a 20 weighted lever adapted to actuate the rod, a movable support on the stove, a shaft depending from said support, a sleeve having a longitudinal slot produced therein, and a stop-pin secured in the shaft and adapted to work 25 in said slot and limit the movement of the support.

DONALD W. ROSS.
